UNITED STATES PATENT OFFICE.

HARRY H. KEEPORTS, OF DETROIT, MICHIGAN.

MEANS AND DIES FOR DROP-FORGING CRANK SHAFTS AND PROCESS OF FORMING CRANK SHAFTS.

Application filed September 5, 1919. Serial No. 321,933.

To all whom it may concern:

Be it known that I, HARRY H. KEEPORTS, a citizen of the United States, residing at Detroit, county of Wayne, State of Michigan, have invented certain new and useful Improvements in Means and Dies for Drop-Forging Crank Shafts and Processes of Forming Crank Shafts, of which the following is a specification.

10 This invention relates to improved means and dies for drop forging crank shafts and to the process of forming the crank shaft.

The object of the invention is to provide improved dies and methods of drop forging crank shafts whereby the structure of the shaft will not be strained or distorted by twisting after the forging operation.

Objects which relate to details will appear from the description to follow.

20 The objects of the invention are accomplished by the devices and means described in the following specification. The invention is defined and pointed out in the claims.

A structure which is a preferred embodiment of the invention is clearly illustrated in the accompanying drawings, forming a part of this specification, in which:

Fig. I is a plan view of the dies for drop forging the crank shaft.

30 Fig. II is an elevation of the dies somewhat separated, looking against the lower side of Fig. I.

Fig. III is a vertical detail sectional view of the dies with a completely forged crank shaft disposed therein, the same being taken on line 3—3 of Figs. I, IV, parts of the crank throws being shown by dotted lines.

Fig. IV is a detail view of the operating faces of the top and bottom dies 1 and 2 placed side by side.

Fig. V is an illustration of the bar from which the crank shaft is formed.

Fig. VI is an outline plan view of the rounded bar after the first bending and shaping operation performed by the die, the oblique impression on the under side being shown by dotted lines and shading being omitted.

Fig. VII is an elevation view of the bar after such preliminary bending and shaping operation.

Fig. VIII is an elevation perspective view of the completely formed crank shaft ready for machining.

55 Fig. IX is a detail sectional elevation on

line 9—9 of Fig. VIII, showing one of the crank throws.

Fig. X is an enlarged detail sectional view on line 10—10 of Fig. VIII, showing a detail of one of the crank pins and the next 60 succeeding throw.

Fig. XI is an end elevation view of this complete crank shaft.

Fig. XII is an enlarged detail sectional view on line 12—12 of Fig. VIII, showing 65 the cross sectional form of one of the crank arms.

Fig. XIII is a detail sectional view on the edge portion of the bottom die, taken on a line corresponding to line 13—13 of Fig. IV, 70 showing the contour of the integral projection.

Fig. XIV is a detail view on the edge portion of the die, taken on line 14—14 of Fig. IV, showing the incline and shape of the die 75 at that point, it being in the opposite direction to that appearing in Fig. XIII, showing the contour of the integral projection 9.

In the drawing, similar numerals of reference refer to similar parts throughout the 80 several views, and the sectional views are taken looking in the direction of the little arrows at the ends of the section lines.

My invention relates particularly to dies and means for forming six throw crank 85 shafts having three crank bearings, one bearing at each end and one at the middle, and generally to any others involving similar manufacturing conditions.

In the process of making my improved 90 crank shaft, I subject the bar to a die action which forms the first and sixth crank throws upwardly, and the third and fourth crank throws downwardly in the same plane, and at the same time, somewhat reduces the bar 95 to form the pin bearings for the second and fifth crank throws at such distance on the shaft that the arms of said throws are formed continuous with the adjacent arms of the first and third at one end and the 100 fourth and sixth at the other end, so that substantially the entire crank shaft is formed, so far as the location of the crank pin and shaft bearings is concerned, by the preliminary operation.

This operation is performed in the edge die of my improved die blocks, and when this is complete the bar is moved to the second die recess or impression, the upwardly projecting first and sixth throws and 110

the downwardly projecting third and fourth throws being turned into a horizontal plane. The action of the second die or recess or impression is to deflect the first and sixth throws upwardly to an angle of sixty degrees and the third and fourth throws upwardly on its side to an angle of sixty degrees from the vertical and to deflect the second and fifth crank pin bearings and 10 throws downwardly into the vertical plane of the shaft. The blank lays on the first and sixth and third and fourth impressions and the balance of the blank moves downward giving the result as stated, with the 15 second and fifth recesses in the bottom die.

It will be seen that by this method there is substantially no stretching of the metal as distinguished from the stretching due to bending after the first forming operation. 20 The arms of the different cranks are simply bent into position and form as seen in Figs. X and XI without undue strain on the metal. At the same time these throws are forged, a portion of the bar is partially upset 25 set ready for the final upsetting operation to form the integral flange.

Of course, after the crank shaft is forged, the fin is trimmed off and the shaft is subjected to finishing action on the die. The 30 shaft after the fin is trimmed off in the trimming dies is replaced in the final forming die and is submitted to further action there-of to finish the forging. The die is specially formed in various particulars to enable it 35 to handle alloy steel.

In this behalf, the terms "up", "down" and "lateral" are only relative, and I describe the structure in the most convenient arrangement. The dies might all, of course, 40 be operated horizontally, or the bottom die might become the top die. For the purposes of defining the invention, these terms will be regarded only as relative.

To make clear the general description 45 above given, I will proceed to describe specifically the operations in conjunction with a specific embodiment of the invention appearing in the drawing. The top die 1 and bottom die 2 have two independent die surfaces, one at the edge which I will call the edge die and the other main die surfaces, which completes the forging of the shaft. The shaft and bar I designate by letter A, and the different crank throws and bearings 50 by reference characters A¹, A², A³, A⁴, A⁵, and A⁶, the index numbers indicating the 55 number of the crank throws.

In carrying out my invention, I place 60 the bar A, see Fig. V, between the edge dies, see particularly Figs. II and IV, and subject it to bending and preliminary forming and shaping action. The first and sixth crank throws, A¹ and A⁶, are bent upwardly 65 into the depressions 4 and 6 on the top die by the projections 3 and 5 on the bottom

die, and the third and fourth crank throws, A³ and A⁴, are deflected downward by the projections 7 and 9 on the top die-cooperating into the depressions 8 and 10 on the bottom die and the bar is slightly reduced 70 in one direction and formed for the crank pins A² and A⁵ of the second and fifth crank throws by the projections 11-12 and 13-14 on the top and bottom dies respectively, see Fig. II. At the same time the end of the 75 bar is somewhat upset and formed and prepared for the final forging and upsetting operations to form the flange integrally with the shaft.

In the handling of alloy steel the projections 3-5 and 7-9 are disposed at an oblique angle to the longitudinal line of the bar and the corresponding depressions are also disposed at an oblique angle to permit the correct and proper shaping or forming 85 of the alloy steel bar, and the central portions and end portions of the die of the edge dies beyond the projections 3-5 are inclined, as indicated by the line in Figs. XIII and XIV, for the same purpose or proper 90 and correct shaping. An inspection of Fig. VI shows the imprint of the projections on the bar and how they make the formation and forging easier when the bar is passed to the second die. If impressions were at 95 right angles to the bar they would be oblique to the shaft bearings after bending.

Where ordinary carbon steel is used, the disposition of these projections and depressions at an oblique angle is not a necessity. 100 They may stand at right angles.

When the bar has taken the preliminary form seen in Fig. VII, it is laid down in the main die, which, in all its parts, is made to conform to the shaft and subjected to 105 the action of completely drop forging the same. This action carries the second and fifth crank pin bearings down in the vertical plane of the shaft to their required positions and the intermediate crank arms accordingly without any particular stretching of the same (aside from what occurs in bending), and the first (A¹) and sixth (A⁶) and the third (A³) and fourth (A⁴) crank 110 throws are deflected relatively to the shaft upwardly through an angle of thirty degrees so that they stand at an angle of sixty degrees to the vertical on each side, which distributes the crank throws in proper 115 relation around the shaft.

The form of one of the arms between the first and second crank throws definitely appears in Fig. X, and the form of the first crank arm is clearly illustrated in Fig. IX, while an end view of the shaft with the disposition of the crank throws and arms appears in Fig. XI, Fig. XII is a cross section of one of the crank arms. Fig. XIII shows the inclination to accommodate the dies to the handling of alloy steel, which is much 120

more highly resistant to the forging process than carbon steel.

In Fig. VIII I show the crank shaft in full lines, to which the main die surfaces are conformed, and I show the flange completely formed thereon, the same being formed by any well known means now in common use.

Of course, there is a parting between the top and bottom dies of the complete molds. This can best be understood by examining the completed crank shaft. I have indicated on Figs. IX and X the line of parting between the top and bottom dies preferred by me, the longitudinal parting being indicated by dotted and full lines on Fig. VIII. This parting may be considerably varied. I show the form which I have found to be highly effective.

In Fig. XIII I show the forming projections for forming the first and sixth crank throws, inclined, with the inclination of the body of the die indicated by dotted lines, and in Fig. XIV I show the corresponding inclination for the third and fourth throws. In Fig. VI the inclination of the impressions made by the projections and depressions are fully indicated in the plan view, those on the under side being indicated by the dotted lines.

By pursuing this method in the forging of crank shafts, undue stretching of the metal is avoided and a six throw three bearing shaft is quickly and effectively formed. It will be observed that by the method I have pursued the stretching of the metal substantially all occurs in the edge die and the crank pin bearings, as well as the shaft bearings, are all substantially located and rough formed in the edge dies. When the blanked bar has passed to the main die, the work to be performed is substantially the final bending and the complete forging of all of the crank throws, that bending being through an angle of sixty degrees in each instance, which is the angle of bending and forging from the vertical central plane, and that there is substantially no upsetting or stretching of the metal between the crank pin bearings and the shaft bearings after the rough shaping in the edger die. The only stretching that occurs is that incident to bending and completing the forming in the final die. This is of great consequence in securing an effective and efficient forging of the shaft. The metal is not weakened, and by placing the projections and depressions at the angle a bar of alloy steel can be readily formed into a crank shaft.

My improved crank shaft is formed with long arms or webs between the first crank pin and the second, and the second crank pin and the third, and the fourth crank pin and the fifth, and the fifth crank pin

and the sixth, in substantially rectangular form. The shorter side of such web or arm in each instance is inclined sufficiently for draft from the die, the minimum being seven degrees from the vertical on work of 70 this length. The opposite side is of such form that it freely flows into the impression of the die and serves to form the balance for the shaft. These arms not being distributed symmetrically about the shaft, 75 it is necessary to project the metal on each arm past the center sufficiently to insure the balance. By this method it is possible to preserve a substantially rectangular cross section of these long arms or webs which insures most economical distribution of metal for carrying the strain.

I have described the form preferred by me, and which I desire to claim specifically. I also desire to claim the same broadly as 85 pointed out in the appended claims.

Having thus described my invention, what I claim as new and desire to secure by Letters Patent is:

1. The process of forming and drop forging a six-throw crank shaft with end and central bearing parts consisting in first deflecting in vertical planes and forming the first and sixth crank throws by upward deflection, and simultaneously the third and 90 fourth crank throws by downward deflection of the metal and rough forming the bearing pins and arms of second and fifth crank throws, then turning the partially formed bar so that the first and sixth, and 95 third and fourth crank throws are in a horizontal plane, and thereafter simultaneously deflecting the shaft to form the second and fifth crank pins and arms to their proper position and simultaneously bending the first and sixth crank throws to deflect them relatively upward thirty degrees to a point sixty degrees to one side of the vertical and the third and fourth crank throws relatively upward thirty degrees to 100 a point sixty degrees to the opposite side of the vertical, as specified.

2. The process of forming and drop forging a six-throw crank shaft with end and central bearing parts consisting in first deflecting in vertical planes and forming the first and sixth crank throws by upward deflection, and the third and fourth crank throws by downward deflection of the metal and rough forming the bearing pins and 115 arms of second and fifth crank throws, then turning the partially formed bar so that the first and sixth, and third and fourth crank throws are in a horizontal plane, and thereafter deflecting the shaft to form the 120 second and fifth crank pins and arms to their proper position, and bending the first and sixth crank throws to deflect them relatively upward thirty degrees to a point sixty degrees to one side of the vertical and the 125 fifth crank pin to a point sixty degrees to the opposite side of the vertical, as specified.

third and fourth crank throws relatively upward thirty degrees to a point sixty degrees to the opposite side of the vertical, as specified.

- 5 3. The process of forming and drop forging a three bearing six-throw crank shaft, consisting in deflecting in vertical planes and forming the first and sixth crank throws by upward deflection and the third 10 and fourth crank throws simultaneously by downward deflection, and rough forming the pin bearings and arms of the second and fifth crank throws, then acting upon the blanked-bar at right angles to the first direction and carrying all the arms and bearings simultaneously to their proper relation in the finishing die, as specified.

- 20 4. The process of forming and drop forging a three bearing six-throw crank shaft 25 consisting in deflecting in vertical planes and forming the first and sixth crank throws by upward deflection and the third and fourth crank throws by downward deflection, and rough forming the pin bearings and arms of the second and fifth crank throws, then acting upon the blanked bar at right angles to the first direction and carrying all the arms and bearings to their proper relation in the finishing die, as specified.

- 30 5. The process of forming and drop forging a shaft having three crank pins between the shaft bearings, consisting in forming the first and third oppositely in the same plane in a suitable die, and thereafter acting upon 35 the bar at right angles to the first direction and carrying the arms and bearings to their proper relation in the finishing die, as specified.

- 40 6. Dies for the forming of a crank shaft comprising depressions and projections with obliquely arranged surfaces for deflecting the first and sixth crank throws in one direction and the third and fourth crank throws in an opposite direction in the same plane, 45 and a finishing die conformed to the form of the shaft and arranged to deflect the second and fifth crank pins, throws and arms to their proper position and forge all crank arms and pins, as specified.

- 50 7. Dies for the forming of a crank shaft comprising depressions and projections with obliquely arranged surfaces for deflecting the first and sixth crank throws in one direction and the third and fourth crank

throws in an opposite direction in the same 55 plane, the surfaces at the center and ends being in planes oppositely inclined to the face of the die, and a finishing die conformed to the form of the shaft and arranged to deflect the second and fifth crank 60 throws to their proper position and forge all crank arms and pins, as specified.

8. Dies for the forming of a crank shaft comprising depressions and projections for deflecting the first and sixth crank throws 65 in one direction and the third and fourth crank throws in an opposite direction in the same plane, and a finishing die conformed to the form of the shaft and arranged to deflect the second and fifth crank throws to 70 their proper position and forge all crank arms and pins, as specified.

9. Dies for the forming of a crank shaft comprising depressions and projections with obliquely arranged surfaces for deflecting the first and sixth crank throws in one direction and the third and fourth crank throws in an opposite direction in the same plane, and a finishing die conformed to the form of the shaft and arranged to deflect the second and fifth crank throws to 75 their proper position, as specified.

10. Dies for the forming of a crank shaft comprising depressions and projections for deflecting the first and sixth crank throws in one direction and the third and fourth crank throws in an opposite direction in the same plane, and a finishing die conformed to the form of the shaft and arranged to deflect the second and fifth crank throws to 80 their proper position, as specified.

11. Dies for the forming of a crank shaft having three crank throws between the shaft bearings comprising depressions and projections for deflecting the first and third 85 crank throws and pins in opposite directions and a finishing die conformed to the form of the shaft and arranged to deflect the second crank throw and shaft bearings to proper position in relation to the said first 90 and third crank pins.

In witness whereof, I have hereunto set my hand and seal in the presence of two witnesses.

HARRY H. KEEPORTS. [L.S.]
